(57) CLAIM

The ornamental design for a pistol, as shown and described.

DESCRIPTION

FIG. 1 is a right side view of the pistol;

FIG. 2 is a left side view thereof;

FIG. 3 is a back view thereof;

FIG. 4 is a front view thereof;

FIG. 5 is a top view thereof;

FIG. 6 is a bottom view thereof; and,

FIG. 7 is a right side view thereof showing the device disassembled.

The broken line showing of FIGS. 1, 2 and 7 are for illustration purposes and form no part of the claimed design.
